UNITED STATES PATENT OFFICE.

WILLIE TAYLOR, OF FARSLY, NEAR LEEDS, ENGLAND.

FIRE-EXTINGUISHING APPARATUS FOR CINEMATOGRAPHS.

Application filed September 28, 1920. Serial No. 413,394.

To all whom it may concern:

Be it known that I, WILLIE TAYLOR, a subject of the King of Great Britain and Ireland, residing at Farsley, near Leeds, in the county of York, England, have invented new and useful Improvements in Fire-Extinguishing Apparatus for Cinematographs, of which the following is a specification.

This invention relates to fire-extinguishing apparatus for cinematographs, and has for its object to provide an improved construction of automatic extinguishing apparatus with which is or may be combined a stop motion and means for extinguishing the electric arc or similar source of illumination in the machine.

Fire-extinguishing apparatus in accordance with my invention comprises a reservoir for fire-extinguishing fluid, an outlet pipe for the fluid connected thereto, an orifice for the fluid in said outlet pipe, a valve normally closing said orifice, means for supporting said valve, a spring tending to move said valve clear of said orifice, and an inflammable connection for retaining said valve closed over said orifice against the action of said spring, said orifice and inflammable connection being disposed immediately above the film gate of the cinematograph. In use, when the film fires, the inflammable connection is immediately fired thereby and breaks, whereupon the spring moves the valve clear of the orifice in the fluid supply pipe and releases a jet of fire-extinguishing fluid therefrom which extinguishes the fire, the film being extinguished in or adjacent to the gate so that only a very short length of film (rarely more than a few inches) is destroyed. I may also provide a pair of spring contacts in the power circuit of the cinematograph, and an insulated contact block normally held in engagement with said spring contacts to close said circuit by said inflammable connection but adapted to be moved out of engagement with said spring contacts by said spring when said connection breaks, whereby the motor driving the machinery which feeds the film is automatically stopped. I may further provide a supplementary contact normally out of engagement

with said spring contacts but adapted to be moved into engagement with one of them when the inflammable connection breaks, and electrically-operated means in series with said supplementary contact for extinguishing the arc lamp of the cinematograph. 55

I will fully describe my invention with reference to the accompanying drawings 60 wherein

Figure 1 is a side elevation of one construction of my improved extinguisher and stop motion;

Figure 2 is a plan, the spool box being removed for clearness; and 65

Figure 3 is a part similar view to Fig. 1 showing the position of the moving parts after operation.

Figure 4 is a diagrammatic plan to a 70 larger scale illustrating one construction of the means for extinguishing the arc lamp of the machine.

Referring first to Figs. 1 to 3 of the drawings, in the construction therein illustrated, 75 11 is a fluid-tight storage reservoir adapted to contain a charge of fluid under pressure which may be air or a fire-extinguishing gas or partly air or gas and partly a fire-extinguishing liquid. The reservoir is 80 mounted in a convenient position above or behind the cinematograph, for example (and as shown) behind the top spool box 12. The reservoir 11 is fitted with a non-return inlet valve 13 of any suitable known 85 construction, and, where a liquid is used, with a filler cap 14. The reservoir 11 is also provided with a pressure gage 15 of convenient known construction, the face of which preferably faces the operator of the 90 machine. 16 is the outlet pipe from the reservoir 11 and leads to a pressure jet orifice 17 in a hollow frame 18, said orifice being located directly above the film gate 19 of the cinematograph. The orifice 17 is 95 normally closed by a valve disc 20 carried by a lever 21 pivoted at 22 which is held in normal position against the action of a spring 23 by a connection 24 (Fig. 1) of cotton strands or other inflammable material disposed directly over the film 25 passing through the gate 19, said connection 24 en- 100

gaging at one side the lower end of the lever 21 and at the opposite side an adjustable hook 26 carried by an arm 27 of the frame 18 which is supported by the upright 5 28 of the machine. The frame 18 also supports the pivot 22 of the lever 21.

The pivoted lever 21 also carries an insulated metallic contact block 29 adapted to normally engage between spring contacts 10 30, 31 in the circuit 32 of the electric motor driving the cinematograph.

It will be seen that, should the film fire as it is passing through the gate 19, the rising flame immediately ignites the cotton connection 24 which breaks, and the spring 23 comes into action and rocks the lever 21 to move the valve 20 clear of the orifice 17 and simultaneously disengages the contact block 29 from between the spring contacts 20 30, 31 thus releasing a pressure jet of fire-extinguishing fluid from the orifice 17 which plays directly on the burning film and extinguishes same, and at the same time automatically stopping the motor driving machinery which feeds the film.

In the arc lamp extinguishing apparatus illustrated in Fig. 4 the pivoted lever 21 also carries, in addition to the insulated contact block 29, a supplementary contact pin 33 30 which normally lies in a groove 34 in the contact 30 out of engagement with it and the other spring contact 31 but which, when the film fires and the inflammable connection 24 breaks and allows the spring 23 to 35 come into operation to disengage the block 29 from the spring contacts 30, 31, makes contact with the contact 30 and current flows from the motor circuit 32 through the pivoted lever 21, spring 23 and frame 18 to 40 a terminal 35 and by a conductor 36 to one of the terminals 37 of an electro-magnet 38, the other terminal 39 of the magnet being earthed. The magnet is thus energized and attracts a pivoted releasing catch 40 which 45 normally engages a switch 41 in the electric arc lamp circuit and holds same closed against the action of a spring 42, but which, when attracted by said magnet 38, disengages the switch 41 and allows the spring 42 to 50 open same and so break the circuit of the arc lamp, so that, when the film fires and the extinguishing apparatus automatically comes into operation to quench the fire as hereinbefore described, not only is 55 the operating motor of the machine stopped but the arc lamp is also extinguished, thus rendering the machine absolutely "dead" and preventing any possibility of the film re-firing, which might occur if the arc lamp continued to burn.

What I claim and desire to secure by Letters Patent is:—

1. In fire-extinguishing apparatus for cinematographs, the combination of a reser-

voir for fire-extinguishing fluid, a fluid outlet pipe connected thereto, said outlet pipe having an orifice, a valve normally closing said orifice, means for supporting said valve, a spring tending to move said valve clear of said orifice, and an inflammable connection for retaining said valve closed over said orifice against the action of said spring, said orifice and inflammable connection being disposed immediately above the film gate of the cinematograph. 65 70 75

2. In fire-extinguishing apparatus for cinematographs, the combination of a fluid-tight reservoir for fire-extinguishing fluid under pressure, a non-return inlet valve fitted thereto, a filler cap, a pressure gage, 80 an outlet pipe for the fire-extinguishing fluid, said pipe having an orifice located directly above the film gate of the cinematograph, a pivoted lever, means for supporting said lever, a valve carried by said lever, 85 said valve normally closing said orifice, a spring tending to move said valve clear of said orifice, and an inflammable connection for retaining said valve closed over said orifice, said inflammable connection being 90 disposed directly over the film gate of the cinematograph.

3. In fire-extinguishing apparatus for cinematographs, the combination of a reservoir for fire-extinguishing fluid, a fluid outlet pipe connected thereto, said outlet pipe having a fluid orifice, a valve normally closing said orifice, means for supporting said valve, a spring tending to move said valve clear of said orifice, an inflammable 95 connection for retaining said valve closed over said orifice against the action of said spring, said orifice and inflammable connection being disposed immediately above the film gate of the cinematograph, a pair 100 of spring contacts in the power circuit of the cinematograph, and an insulated contact block carried by said valve supporting means and normally held by said inflammable connection in engagement with said 105 spring contacts to close said circuit but adapted to be moved by said spring out of engagement with said contacts when said connection breaks.

4. In fire-extinguishing apparatus for 115 cinematographs, the combination of a reservoir for fire-extinguishing fluid, a fluid outlet pipe connected thereto, said outlet pipe having a fluid orifice, a valve normally closing said orifice, means for supporting said valve, a spring tending to move said valve clear of said orifice, an inflammable connection for retaining said valve closed over said orifice against the action of said spring, said orifice and inflammable connection being 120 disposed immediately above the film gate of the cinematograph, a pair of spring contacts in the power circuit of the cinematograph, the combination of a fluid-tight reservoir for fire-extinguishing fluid, a fluid outlet pipe connected thereto, said outlet pipe having an orifice, a valve normally closing said orifice, means for supporting said valve, a spring tending to move said valve clear of said orifice, an inflammable connection for retaining said valve closed over said orifice against the action of said spring, said orifice and inflammable connection being 125 disposed immediately above the film gate of the cinematograph, a pair of spring contacts in the power circuit of the cinematograph.

graph, an insulated contact block carried by and electrically-operated means automatically operated for extinguishing the arc
said valve-supporting means and normally held by said inflammable connection in engagement with said spring contacts to close lamp of the cinematograph when said valve 10
is moved away from its seat.

5 said circuit but adapted to be moved by said spring out of engagement with said spring contacts when said connection breaks, In testimony whereof I have signed my name to this specification.

WILLIE TAYLOR.
